UNITED STATES PATENT OFFICE.

SAMUEL HAYWARD, OF BOSTON, MASSACHUSETTS, ASSIGNOR TO J. ESTEY & CO., OF BRATTLEBOROUGH, VERMONT.

DESIGN FOR ORGAN-CASE.

Specification forming part of Design No. 6,679, dated May 27, 1873; application filed April 25, 1873.

To all whom it may concern:

Be it known that I, SAMUEL HAYWARD, of Boston, in the State of Massachusetts, have invented a Design for an Organ-Case, of which the following is a specification:

The nature of my design is fully represented in the accompanying photographic illustration, to which reference is made.

My design for the front or front board of the organ-case consists of the shape of the inverted ornamental brackets at each side of the blow-pedals, and extending upward toward the key-board, and which are connected near their top with an ornamental bar or roll extending horizontally across the front board of the case; and also in the combination therewith of a pendent ornamental figure arranged between said brackets on the front.

The front board of the organ-case is represented by *c c c*, *d d* being the pedals, at each side of which is situated a bracket, *b*, in inverted position, its smaller extremity extending upward toward the key-board *e* of the instrument. Extending horizontally across the

front of the case, and united with the upper portion of the brackets *b b*, is formed the ornamental bar or roll *a a*, and depending centrally therefrom is the ornamental figure *f*, which occupies a central position on the front between the brackets. These figures impart to the front of the case an ornamental and varied appearance, relieving it of the monotony of a plain surface.

I claim as my invention—

1. The design for the front of an organ-case, consisting of the bar *a a*, in combination with the brackets *b b*, substantially as herein shown and described.

2. The pendent ornament *f*, in combination with the bar *a a*, substantially as shown and described.

In witness whereof I have hereunto signed my name in the presence of two subscribing witnesses.

SAMUEL HAYWARD.
